P. QUINN.
STEAM GENERATOR.

No. 75,296.

Patented Mar. 10, 1868.

United States Patent Office.

PATRICK QUINN, OF SOUTH NEWMARKET, NEW HAMPSHIRE, ASSIGNOR
TO HIMSELF AND CHARLES R. PAUL, OF SAME PLACE.

Letters Patent No. 75,296, dated March 10, 1868.

IMPROVEMENT IN STEAM-GENERATORS.

The Schedule referred to in these Letters Patent and making part of the same.

TO ALL TO WHOM THESE PRESENTS SHALL COME:

Be it known that I, PATRICK QUINN, of South Newmarket, in the county of Rockingham, and State of New Hampshire, have invented certain new and useful Improvements in the Construction of Steam-Boilers or Generators; and do hereby declare the following to be a full, clear, and exact description thereof, due reference being had to the accompanying drawings, making part of this specification, and in which—

Figure 1 is a vertical central and longitudinal section, and

Figure 2 a top view or plan of my invention.

Figure 3 a side elevation, and

Figure 4 a top view of the generator and superheating-device, with the outer casing or "jacket" of the generator removed.

One object I have had in view in making this invention is to superheat the steam, to some extent, in its passage from the generator, and to consequently take it therefrom in a "dry" state, as it is termed, the advantage of this being well understood and appreciated by engineers and others conversant with the production and use of steam.

Another object sought and accomplished in this invention is to utilize and economize the latent heat contained in the smoke and gaseous products of combustion, much of which has heretofore been lost by escaping into the chimney, or by not being applied to available points.

The first object, that is, superheating the steam, is accomplished by placing upon the top of the generator, which, in the present instance, is an upright-flue generator, a spiral or coiled pipe, one end of which communicates with the interior or steam-space of the generator, and the opposite end communicating with the pipe leading to the engine, or object to which the steam is introduced, a circular, perforated shield or deflector being disposed within the coil to deflect the heat issuing from the generator-flues, about the coil, substantially as hereinafter explained.

The second-mentioned object of the present invention is attained by enveloping the generator with a cylindrical jacket or casing, and combining with such jacket a direct and indirect smoke-discharge flue, by means of the latter of which the smoke and gases are caused to descend within and circulate about the interior of such jacket, and in contact with the exterior of the generator, by which means their latent heat is extracted, and a considerable portion of it expended upon such generator and utilized.

By referring to the accompanying drawings, above mentioned as illustrating my invention, it will be seen that the generator is shown at A, as composed of a cylindrical shell, *a*, heads *b*, and tubes *d d*, &c., constructed in the ordinary manner of upright-flue boilers, with the exception of being open at the bottom. The fire-box or furnace of such generator is shown at B, as composed of an annular cylindrical trough or box, of the same diameter as that of the generator, and when applied to the generator, serves as a bottom and as a continuation of the water-space thereof, such fire-box being constructed with the usual grate and fuel-supply door and ash-pit. For convenience of securing the fire-box to the shell of the generator, I bolt securely the outer ends of each to an annular flange *e* or *f*, the outer circumference of the latter being somewhat larger than the former, in order to serve as a bed or resting-place for the jacket, to be hereinafter referred to. The two flanges, *e* or *f*, are to be in turn bolted together, as shown in the drawings, thus securely fixing the fire-box to the generator, and at the same time allow of its ready removal therefrom, for the purpose of substituting a new one, should this become necessary.

The outer and heat-enclosing jacket, before mentioned, is shown at *g* as composed of a cylindrical shell, closed at top, and somewhat larger in diameter than that of the generator which it envelopes, in order to form an annular warm-air chamber, *h*, between the two, the lower end of the jacket resting upon and being supported in position, in part, by the lower flange *f*, and the upper flange *e*, about which it fits tightly. The jacket *g* rises above the top of such generator to such a distance as to form a chamber, *j*, above the top of such generator, and between the two, the top of the jacket being provided with a transverse direct flue, *k*, for carrying off the smoke and gaseous products of combustion, when kindling a fire within the furnace, or for accelerating the draught upon such fire. The lateral flue *l* communicates with an upright flue, *l*, the upper end of

which leads to the chimney, and the lower end of which communicates with the lower part of the air-space or chamber *h*, by an aperture or opening, *m*, a damper, *n*, being applied within the lateral flue *k*, between its point of communication with the generator and the flue *l*.

The superheating-device, to which allusion has before been made, is composed of a spirally-coiled pipe, *o*, placed upon the top of the generator, and extending up to or nearly to the top of the jacket *g*, and in close proximity to its inner periphery, as shown in the accompanying drawings, the lower extremity of such coiled pipe leading into the steam-space *p* of the boiler, while its upper end is carried through the top of the jacket, from whence it is to be extended to the desired point. An upright annular shield or deflector, *q*, is placed upon the top of the generator, and within, and circumscribed by the coiled pipe *o*, and extends between the top of such generator and the top of the jacket *g*, and forms a tight joint between the two, and shutting off communication between the warm-air chamber *h* and the direct-draught flue *k*; the said annular deflector being pierced with a series of holes *r r*, &c., at or near its top.

As the steam issues from the generator into and through the coiled pipe *o*, which is heated by the products of combustion passing through the generator-flues, such steam is "superheated," and the moisture or water taken up by it, in larger or smaller quantities, is vaporized and utilized, instead of passing off in the exhaust, the coiled pipe being a simple, cheap, and very effective device for accomplishing this result.

Upon opening the damper *n* in the lateral flue or pipe *k*, the draught will be directly upward, through the generator-flues, and into the chimney. By closing the damper *n*, the current of products of combustion, as they issue from the flues *d d*, will come in contact with the deflector *q*, and be deflected through its holes or apertures *r r*, &c., from whence they will descend into the chamber *h*, and be drawn into the upright flue *b*, and escape into the chimney, thus in their passage impinging against the outer area of the coiled pipe, and heating it, and giving up their latent heat to and in heating the generator, or water contained therein. The space or chamber *h* thus becomes, not only a warm-air chamber, but a flue.

It may be found, in practice, desirable to place in this chamber, and between it and the generator, a spiral partition, in order to cause the products of combustion to circulate entirely around its area. It is hardly necessary to mention that a safety-valve is to be applied to the generator in any suitable manner.

I would remark here, that an aperture or opening should be made through the walls of the fire-box, for the purpose of admitting cold air thereto, and to aid in the combustion of the gases arising from the fire.

What I claim, and desire to secure by Letters Patent of the United States of America, is as follows:

I claim the combination and arrangement of the coiled pipe *o*, deflector *q*, jacket *g*, and flues *k* and *l*, the whole being arranged and operating together to produce the results before described.

PATRICK QUINN.
